DISPENSING UNIT

Howard Tebay, Wheeling, W. Va.; Ireta J. Tebay, administratrix of said Howard Tebay, deceased

Filed Dec. 26, 1956, Ser. No. 630,610

7 Claims. (Cl. 194—57)

This invention relates to dispensing apparatus, and more particularly to means in such apparatus for releasing and locking a product take-out gate, which means are coin controlled.

In one well known type of dispensing apparatus, particularly adapted for dispensing bottled goods, the bottles are manually moved to a take-out position closed by a gate or gates, which, when released, will open as the bottle is lifted to permit the bottle to be removed from the dispenser. Various means have been employed for holding the gates against movement, and for releasing them for movement when desired.

It is the object of the present invention to provide improved gate controlling means which, in turn, is controlled by a coin or coins inserted in the dispenser in payment for the goods to be dispensed.

It is an object to provide such means wherein a single coin or combination of coins may be used to release the gate locking means.

Another object is to provide a gate control which can be readily converted to be operative upon the insertion of a different coin or combination of coins.

A still further object is the provision of such means in a unit which may be used to replace the delivery units now being used.

Other objects of the invention will become apparent from the following description of one practical embodiment thereof, when taken in conjunction with the drawings which accompany, and form part of, this specification.

In the drawings:

Figure 1 is a perspective view of a dispensing cabinet with the lid and front open and the dispensing unit and control mechanism therefor in place on the front panel;

Figure 2 is a fragmentary plan of the cabinet with the top removed;

Figure 3 is a perspective view of the dispensing unit, enlarged but similar to the showing of the unit in Figure 1;

Figure 4 is a perspective view of the dispensing unit viewed from the opposite side;

Figure 5 is a vertical section through one corner of the dispensing unit housing, illustrating the delivery gate mounting and control mechanism therefor, and taken on the line 5—5 of Figure 3;

Figure 6 is a vertical section taken on the line 6—6 of Figure 4;

Figure 7 is a top plan view of the gate locking and releasing mechanism;

Figure 8 is a vertical section through the mechanism shown in Figure 7 and is taken on the line 8—8 of Figure 7; and

Figure 9 is a vertical transverse section through the coin control.

Referring to the drawings in detail, there is shown a dispensing box or cabinet 1, of well known type, such as is used to dispense cooled bottled beverages. The cabinet has thick insulated walls 2 and a lid 3. The space

2

within the cabinet is divided into a storage compartment 4 and a dispensing unit compartment 5. The storage compartment is provided with a plurality of spaced, parallel, rack bars 6 which serve to form guide channels to receive the necks of bottles 7 and hold them in rows. A passage 8, between the ends of the guide bars and the dispensing unit 9, permits the bottles to be moved out of the rows singly and to the entrance 10 of the delivery chamber 11 of the dispensing unit. The top of the delivery chamber is blocked by a pair of hinged gates 12, and a bottle in the chamber may be removed from the cabinet by lifting upward to swing the gates open. All of the above is conventional, and the present invention is concerned with the dispensing unit.

The dispensing unit consists of a coin control mechanism, the delivery chamber and interconnecting linkage for locking and releasing the outlet gates. The coin control 13 is within a chamber 14 while the delivery chamber 11 is within the refrigerating area. Both the coin control and the delivery chamber are fixed to the front door 15 of the box. The coin control chamber is completely surrounded by an insulating wall 16 which provides the necessary heat barrier between the unit and the storage compartment. The chamber is completed by the insulated back wall 17.

In the coin control chamber, there is a conventional coin reject mechanism 18, connected to the door 15 and positioned beneath a coin slot or slots 19 in the top of the insulating wall 16. Slugs, or coins of improper size, will be rejected by this mechanism in well-known manner and drop out through a suitable reject tube.

When a coin or coins of proper value are put into the unit, they will be directed by the reject mechanism into a coin operated locking device 20, mounted in the coin control chamber directly below the reject mechanism. This device will be locked against movement when no coin is in it, and when a coin or coins of proper value are in place will be free for movement to permit the gates to open as will be described.

The locking device is supported upon a bracket 21, fixed to a holder 22 attached to the door 15, which also supports the reject mechanism 18. The bracket is secured by screws 23 to the base member 24 of the locking device. The central portion of the upper face of the base member is grooved out, as at 25, to form a trackway for the moving parts of the locking device. Angle members 26 are fixed to the upper side edges of the base member and project over the sides of the groove to form channel grooves 27 to guide the moving parts and lock them to the track.

A sliding carriage 28 is mounted in the trackway. The carriage is a casting, longitudinally grooved on either side of the center to provide side walls 29, a central draw-bar 30, and the grooves 31 and 32. The draw-bar extends the full length of the carriage and projects forwardly beyond the carriage to provide means for connection to linkage which will be described. The two slots are of different lengths and adapted to receive slugs 33 of different sizes to adjust the slot length to that required to receive a coin or coins of selected denomination. The size slugs used will determine the coins necessary to operate the device, as will appear.

The forward ends of the side walls of the carriage are inclined rearwardly, to provide cam surfaces 34 up which locking bars 35 may ride. The inclined ends are provided with notches 36 into which the locking bars will drop, if no coin is in the carriage, and prevent carriage movement. The locking bars are pivotally connected to the angle members 26, as at 37, and have inwardly projecting cam following and locking members 38 at their forward ends. The cam following members each overlie one of the slots 31 or 32 between the draw-

bar and side members adapted to receive coins. If a coin of proper denomination is in position in one of the slots, its peripheral edge will bridge the notch on the adjacent side member so that the locking bar will ride completely up the incline when the carriage is moved forward. The two locking bars may be joined for simultaneous movement by means of a sleeve 39 slipped over the pins 38. If two coins are to be used, one in each slot, the locking bars will be left free to operate independently so that coins will have to be present in both slots to cause both locking bars to lift to free the carriage.

It will be noted that the sides of the draw-bar are inclined toward one another, and the inner faces of the spacers are inclined in the same area. This will provide entrance throats to lead coins to the slots.

The movable carriage of the locking device is connected to the gates 12, to hold the gates against opening until the proper sum has been put into the machine. This is accomplished by appropriate linkage connected to the gates, to the locking unit, and to a pivoted lever plate which coordinates the movement of the linkages and transfers movement from one to the other.

The lever plate 40 is pivotally mounted on the back of a housing 41 which defines the delivery chamber. It is to this housing that the gates 12 are pivotally connected. Each gate has pivotally connected to it at 42 one end of a link 43, the other ends of the links being connected to a common pivot 44 on the plate 40. The pivots 42 are offset from the pivotal mountings of the gates so that when the gates are raised the levers will be moved downwardly. This will cause the lever plate to rock downwardly (as viewed in Figure 4) about its pivot 45. Plate 40 is biased to its upward position by a spring 46 and its limits of movement are defined by a pin 47 projecting from the housing 41 and passing through an arcuate slot 48 in the plate 40.

Movement is transmitted from the plate 40 to the locking unit by a link 49, pivotally connected to the draw bar 30 and having a pin 50 projecting from the link through a slot 51 in the plate 40. Slot 51 is of dog-leg shape having a reach 52 and a reach 53. Movement of the pin 50 in the slot is controlled by a governing arm 54, which is connected to the pin at one end and pivotally mounted upon a bracket 55 near the top of the housing 41. It will be obvious that downward movement of the plate 40 will cause the edge of the reach 52 of slot 51 to act as a cam against pin 50 to draw link 49 and the locking unit sliding carriage forwardly. Pin 50 will be guided along reach 52 of slot 51 by swinging movement of control arm 54. Pin 50 will reach the juncture of the two reaches of the slot after carriage 28 has moved far enough to eject the coin or coins controlling it, as will be described. The remainder of the movement of the plate 40 can be accomplished while pin 50 moves along the reach 53 of slot 51 and there will be no further movement of the locking unit carriage. As the plate reverses its movement the pin will move in reverse along the slot, the carriage being returned by spring 56. Pin 50 striking the end of slot 51 will serve to limit the return movement of the carriage 28.

In order to ensure carriage 28 making its full movement so that the coin or coins will be dropped, thus eliminating the possibility of more than one bottle being dispensed without inserting extra coins, the plate is required to have a greater amplitude of movement than that actually required. This is accomplished by providing a plurality of teeth 57 along the edge of plate 40 and a pawl member 58 for contact with the teeth. The pawl consists of a disk 59, pivotally mounted on the housing 41 and having a pin 60 extending from it. A spring 61 urges disk 59 to a position where pin 60 is in alignment with pivot 45 of plate 40 and the pivotal mounting of disk 59. The pin is mounted a greater distance from

10
15

the center of the disk 59 than the projected arc of travel of the bottoms of the spaces between the teeth 57. Thus, when plate 40 begins to move pin 60 will be contacted by the teeth and the disk rotated slightly. The disk will be unable to return to its position of rest while the toothed section of the plate is in engagement with pin 60. Therefore, the plate will be unable to reverse its movement until the entire toothed area of the plate has passed beyond the pin and the pin drops into the recess 62. This will permit the pin to assume its position of alignment with the two mentioned pivots and the plate movement can be reversed. Once the reverse movement has started, the toothed area must again be moved entirely across the pin before gate opening movement can begin again.

As the gates are moved to open position, the entrance to the delivery compartment is blocked so that another bottle cannot be brought into the chamber until the gates are closed again. The blocking mechanism consists of two links 63, pivotally connected at their bottoms to the free ends of cranks 64 pivotally mounted on the housing 41 at opposite sides of the entrance door. The tops of the links are connected to arms 65 fixed to the gates 12. When the gates are raised, the links swing inwardly toward each other and across the entrance into the chamber.

In using the dispenser the locking device is first set to operate when the proper coin or coins are inserted. To do this, slugs of proper size are positioned in the slots of carriage 28 to leave the end of the slots open to accommodate the desired coin. For example, slugs may be inserted on one side so that when a nickel is deposited it will drop into the locking device in position to have its edge block out the notch in the adjacent side wall. If a dime is to be received in the other side, the slug on that side will leave a smaller space to the end of the carriage so that the dime will block out the notch in that side wall. When the coins are in place, the gates can be lifted, as the locking bars will ride up the ends of the side walls permitting the carriage to move freely in a forward direction. It will be obvious that slugs may be used to size the slots to receive any coin or combination of coins. As mentioned above, one side only may be used to receive a coin, whereupon the two locking arms will be joined together. As the carriage moves forward and the locking bars lift, the coins will be free to drop out into any suitable receptacle.

While in the above one practical embodiment of the invention has been disclosed, it will be understood that the precise structural details described and shown are merely for purposes of illustration and the invention may take other forms within the scope of the appended claims.

What is claimed is:

55 1. In a dispensing unit for bottled beverages of the type having an outlet through which bottles may be removed, the improvement which consists in a pair of pivotally mounted gates normally blocking the outlet, a coin controlled mechanism normally holding the gates against opening movement, a sliding carriage forming part of the coin controlled mechanism and releasable for sliding movement by insertion of the proper coins, a lever pivotally connected to the unit, links pivotally connected to the gates and the lever, and a draw-bar link pivotally connected to the sliding carriage and the lever, the connection between the draw-bar link and the lever having means providing for lost motion so that the lever may continue rocking movement about its pivotal connection to the unit after the sliding carriage has reached its limit of movement.

70 2. In a dispensing unit for bottled beverages as claimed in claim 1, means to prevent reverse movement of said lever after movement has been instituted in one direction until full movement in said one direction has been completed.

3. In a dispensing unit for bottled beverages as claimed in claim 1, the connection between the lever and the draw-bar link including said lever having a slot with a cam portion therein, a pin projecting from the end of the draw-bar link to ride in the slot whereby rocking of the lever through the camming action of the slot on the pin will move the draw-bar link to slide the carriage, said slot having a lost motion portion so positioned that the lever may rock without imparting movement to the draw-bar link, the cam and lost motion portions of the slot having relative positions such that the pin will be in the cam portion at the outset of the opening movement of the gates and in the lost-motion portion after the slide has reached its limit of movement and the gates are in the final stage of opening movement.

4. In a dispensing unit for bottled beverages as claimed in claim 3, means to prevent reverse movement of said lever after movement has been instituted in one direction until full movement in said one direction has been completed.

5. In a dispensing unit for bottled beverages as claimed in claim 3, an additional link pivotally connected to said unit and to the draw-bar link adjacent the pin to support the pin end of the draw-bar link when it is in the lost motion portion of the slot.

6. Control means for a dispensing unit for bottled beverages of the type having a delivery chamber with an entrance for bottles to be dispensed and an outlet for bottles comprising, gates normally blocking said outlet and pivotally connected to said unit, a lever plate pivotally connected to the unit, links connected to the gates

5 offset from the pivotal connections thereof and to the lever plate at a common point offset from the pivot of the plate whereby movement of the gates will move the plate, a sliding carriage normally locked against sliding movement but releasable for sliding by insertion of a proper coin, a link connecting said carriage to the plate whereby the carriage controls movement of the lever plate, and means included in the connection between the plate and the link from said carriage to permit the plate 10 to move after the carriage has reached its limit of movement.

7. In control means for a dispensing unit as claimed in claim 6, means to prevent reverse movement of said lever after movement has been instituted in one direction 15 until full movement in said one direction has been completed.
